UNITED STATES PATENT OFFICE.

LEON MITELMAN, OF CHICAGO, ILLINOIS.

WAVE MOTOR.

1,420,332.

Specification of Letters Patent. Patented June 20, 1922.

Application filed June 2, 1921. Serial No. 474,343.

To all whom it may concern:

Be it known that I, LEON MITELMAN, a citizen of the Government of Ukraine, residing at Chicago, in the county of Cook 5 and State of Illinois, United States of America, have invented certain new and useful Improvements in a Wave Motor, of which the following is a specification.

My invention relates to motors and more 10 particularly to that class of apparatus known as wave-motors wherein the rise and fall of the waves with respect to the motor and its support will cause a rotation of the drive shaft of the apparatus.

Heretofore, so far as I am aware, most 15 wave or tide motors have relied solely upon having a fixed structure securely anchored so that the rise and fall of the waves or tide will cause a movement of the drive shaft, 20 whereas in my present invention I rely more or less on the submergence of the actuating means into the water during the pitch or roll of a body floating upon or borne upon the surface of the water such as a boat or 25 vessel, and my invention is especially capable of being effectively employed when the vessel is in motion as when travelling from place to place. Also I have so designed and arranged the actuating mechanism that the 30 structure which operates upon a downward movement of the boat is rendered ineffective upon the upward movement of the boat, and vice versa. Furthermore, I have so designed my generator that the depressing of the 35 structure in the water will be effective upon one particular mechanism or element, whereas as the lifting of the structure will operate another mechanical element, but both these elements are so designed and are mounted 40 upon a common shaft that is driven in but one direction by the two mechanisms.

I prefer to carry out my invention in substantially the manner hereinafter described, the drawing illustrating a typical structure 45 and is merely diagrammatic for the purpose of disclosing the principles involved.

In the drawings:

Figure 1 is a longitudinal view of a type 50 of installation of my invention the same being shown within the hull of a vessel at the bow and stern thereof.

Figure 2 is a plan of the vessel showing 55 the decks at the bow and stern broken away to disclose the installation of my invention in the hull.

Figure 3 is a vertical axial section of the

actuating mechanism of my motor and drawn to a larger scale than the preceding figures.

Figure 4 is a transverse section thereof 60 taken on line 4—4, Figure 3.

Figure 5 is a schematic illustration of the operation of a closure device in connection with the blades of the turbines or wheels.

Figure 6 is a view similar to Figure 1 65 illustrating the manner of installing my invention upon the exterior of the hull of the vessel.

Figure 7 is a stern view of the structure 70 illustrated in Figure 6.

Figure 8 is a sectional view taken on the vertical axis of the actuating mechanism illustrated in Figures 6 and 7, drawn to a larger scale and provided with a hinged 75 valve closure for turbine blades.

Figure 9 is a transverse section taken on line 9—9 of Figure 8.

Figure 10 is a fragmentary detail in section, of the valve or closure, taken on line 80 10—10—Figure 9.

The manner of installing and utilizing 85 my invention is capable of various embodiments and to this end I have illustrated two types which contemplate the use of my motor both inside and outside the hull of a navigable vessel. It of course will be appreciated that a scow or other suitable float may be utilized in lieu of the vessel without altering or changing the principles of operation of my invention.

In Figures 1, 2, and 3, the motor is installed inside the vessel, and to do that I provide one or more chambers or compartments 15 within the hull 16, preferably at the bow and stern thereof. These compartments are preferably constructed in such manner that they may be freely opened to the sea or body of water in which the vessel is floating but may be readily closed in the event the turbine or motor is not being operated. This is done by cutting out portions 17 in the wall of the hull adjacent the compartments and providing suitable doors 18 therefor that are hinged or otherwise mounted and which are provided with gaskets or otherwise constructed to render the same water-tight when the doors are closed. It will of course be understood the walls of the chamber within the hull are water-tight to prevent leakage into the hold of the 100 vessel.

As the compartments 15 and the operating

mechanism therein are the same throughout, I will proceed to describe but one for the purpose of convenience. Adjacent the bottom of the chamber 15 is a thrust-bearing 19 that journals and supports a vertically disposed rotatable shaft 20 that is positioned axially in the compartment and passes through the top thereof where it is journaled in a bearing collar 21 and the upper portion or end of this shaft is suitably connected to any mechanism it is desired to actuate, such as an electric-generator, air-compressor, etc., indicated diagrammatically at 22 in the drawings.

15 Intermediate the top and bottom of the compartment two sets of blades or turbines are rigidly secured to the shaft 20, the upper being designated as 23 and the lower as 24, that are spaced apart a suitable distance and 20 have their blades disposed in opposite directions with respect to each other. This arrangement is illustrated in the sketches comprised in Figure 5 of the drawings, the object of such an arrangement being to permit 25 the lower turbine 24 to be actuated when the structure is being depressed or moved downwardly in the water and the upper turbine 23 to be actuated upon an upward movement of the structure, so that the shaft 20 will be 30 rotated in but one direction. To further assist in carrying out this principle of my invention I have provided a sliding sleeve 25 upon the shaft 20 between the turbines and at the opposite ends of said sleeve I secure 35 disks 26 and 27 of approximately the diameters of the respective turbines. These disks are of buoyant or semi-buoyant material preferably wood or the like, and in operation one disk will lie against the adjacent face of 40 its respective turbine while the opposite disk is away from its turbine;—in other words, the disks act as valves to "open" or "close" the turbine members according to the direction of movement of the structure in the 45 water.

As seen in Figure 3 of the drawings the structure is being moved upwardly in the water and the upper valve is open to permit the water to flow through the upper turbine 50 member and rotate the same while the lower valve is closed rendering the lower turbine unsusceptible to the action of the water which discharges above the disk 27 out of the compartment and back into the sea as 55 indicated by the arrows. The action of the valves and the respective turbine members with respect to the flow of water through the structure in both directions is indicated in the schematic sketches forming Figure 5 in 60 which the vertical arrows indicate the flow of the water and not the direction of movement of the vessel or compartment in a vertical direction, such as the pitch and scend in riding the waves.

65 In the structure illustrated in Figures 6

to 10 of the drawings, the casings and turbines in the form of units are provided that are mounted at divers locations upon the outside of the hull of the vessel as indicated in Figures 6 and 7, and hinged valve-plates 70 or closures are employed for each turbine member in lieu of the reciprocating sleeve and disks heretofore described.

The casing 30 of this type of structure is of cylindrical shape throughout its intermediate or central portion and the upper and lower ends thereof are flared or funnel-shaped as at 31 in the drawings, the structure being secured to the hull in any suitable manner. In the lower end of the casing I 75 mount the thrust bearing 32 that supports and journals the lower end of the rotatable driving shaft 33 the upper portion of which passes through a suitably packed opening and bearing in the wall of the hull and extends into the boat structure preferably below the deck where it may be readily connected to any suitable mechanism as in the first-described type of structure. Within the intermediate portion of the casing 30 I 80 mount the upper and lower turbines or propellers, 34 and 35 respectively, upon the shaft 33 with the blades or vanes of one turbine disposed in opposite inclinations to those of the other, and between the transverse or horizontal planes of these turbines I prefer to cut-away the greater portion of the casing to permit of the ready discharge 85 of the water through large openings 36.

In order to permit the oppositely arranged turbines to function in the manner heretofore described I have provided their facing or adjacent portions with a plurality of flat segmental shaped valve-plates 37 of any suitable material that are hinged at 90 to the turbine members (or to their frames) so that when the movement of the vessel causes a depression of the casing the water will flow upwardly through and act upon the lower turbine 35 but will pass out through 95 the openings 37 because the closure of the valve-plates on the upper turbine 34 will prevent it acting thereon, and when the vessel causes a lifting action on the casing the reverse operation takes place, it being understood; however, that both the up and down motion of the casing in the water will cause a rotation of the shaft 33 in one direction and this movement of the shaft will be substantially continuous so long as the vessel is subjected to the action of the waves. 105

In the operation of my apparatus it will be understood that the roll or motion of the vessel is not alone relied upon for the operation of the turbines and their connected 110 shaft, but this same effect is obtained upon a large vessel where the roll is but slight and the up and down motion of the waves passing the boat will perform the function 115 desired.

What I claim is:—

1. A motor comprising a float, an elongated casing rigidly secured thereto and below the water-line of said float, a rotatable shaft positioned in said casing and extended upwardly out of the same, means for mounting said shaft, rotatable devices secured to said shaft within said casing in spaced relation to each other, one of said devices affected by the passage of water through said casing in one direction and the other devices affected by the passage of water in the opposite direction, whereby said shaft is continuously rotated in a given direction. 5
- 10 2. A motor comprising a float, an elongated casing rigidly secured thereto below the water-line of said float, a rotatable shaft positioned in said casing and extended upwardly out of the same, means for mounting said shaft, rotatable devices secured to said shaft within said casing in spaced relation to each other, one of said devices affected by the passage of water through said casing in one direction and the other device affected by the passage of water in the opposite direction, whereby said shaft is continuously rotated in a given direction, said casing intermediate said rotatable devices provided with outlet ports to discharge the 15 water moving through the casing in either direction. 20
- 25 3. A motor comprising a float, an elongated casing rigidly secured thereto and below the water-line of said float, a rotatable shaft positioned in said casing and extended upwardly out of the same, means for mounting said shaft, rotatable devices secured to said shaft within said casing in spaced relation to each other, one of said devices affected by the passage of water through said casing in one direction and the other device affected by the passage of water in the opposite direction, whereby said shaft is continuously rotated in a given direction, and 30 control members upon each rotatable device adapted to render the respective device ineffective when the water flow is moving in a direction opposite to that required to actuate the respective device. 35
- 40 4. A water motor comprising a float, a submerged elongated casing supported thereby and provided with outlet ports intermediate its ends, a thrust bearing in the 45
- 50 lower portion of said casing, a rotatable shaft mounted in said bearing and extended upwardly out of said casing, turbine wheels mounted upon said shaft within said casing in spaced relation to each other upon opposite sides of said outlet ports and having their blades arranged in opposite directions, and closure means for each turbine wheel whereby when the water is passing through one of said turbine the blades of the other turbine are unaffected by the flow of water and vice versa. 55
- 55 5. A wave motor comprising, in combination with a float, a rotatable shaft journaled thereon, upper and lower turbines mounted on said shaft, and means that alternately cover and open said turbines to the passage of water therethrough, whereby the downward movement of said float causes the water to flow through and actuate the lower turbine and the upwardly movement of said float causes the water to flow through and actuate the upper turbine. 60
- 60 6. A wave motor comprising, in combination with a float, a turbine actuated by the relative movement between the water and float in one direction, a second turbine actuated by the relative movement between the water and float in the opposite direction, and a common shaft journaled on said float to which said turbines are secured, said shaft being rotated in one direction by the movement of both turbines. 65
- 65 7. A wave motor comprising, in combination with a float, a turbine actuated by the relative movement between the water and float in one direction, a second turbine actuated by the relative movement between the water and float in the opposite direction, a common shaft journaled on said float to which said turbines are secured, said shaft being rotated in one direction by the movement of both turbines, and valve devices adapted to alternately open and close said turbines to the passage of the water therethrough. 70
- 70 8. A wave motor comprising, in combination with a float, a rotatable shaft journaled on said float, upper and lower turbines mounted on said shaft, and means that alternately cover and open said turbines to the passage of water therethrough, whereby the downward movement of said float causes the water to flow through and actuate the lower turbine and the upwardly movement of said float causes the water to flow through and actuate the upper turbine. 75
- 75 9. A wave motor comprising, in combination with a float, a turbine actuated by the relative movement between the water and float in one direction, a second turbine actuated by the relative movement between the water and float in the opposite direction, and a common shaft journaled on said float to which said turbines are secured, said shaft being rotated in one direction by the movement of both turbines, and valve devices adapted to alternately open and close said turbines to the passage of the water therethrough. 80
- 80 10. A wave motor comprising, in combination with a float, a rotatable shaft journaled on said float, upper and lower turbines mounted on said shaft, and means that alternately cover and open said turbines to the passage of water therethrough, whereby the downward movement of said float causes the water to flow through and actuate the lower turbine and the upwardly movement of said float causes the water to flow through and actuate the upper turbine. 85
- 85 11. A wave motor comprising, in combination with a float, a rotatable shaft journaled on said float, upper and lower turbines mounted on said shaft, and means that alternately cover and open said turbines to the passage of water therethrough, whereby the downward movement of said float causes the water to flow through and actuate the lower turbine and the upwardly movement of said float causes the water to flow through and actuate the upper turbine. 90
- 90 12. A wave motor comprising, in combination with a float, a rotatable shaft journaled on said float, upper and lower turbines mounted on said shaft, and means that alternately cover and open said turbines to the passage of water therethrough, whereby the downward movement of said float causes the water to flow through and actuate the lower turbine and the upwardly movement of said float causes the water to flow through and actuate the upper turbine. 95
- 95 13. A wave motor comprising, in combination with a float, a rotatable shaft journaled on said float, upper and lower turbines mounted on said shaft, and means that alternately cover and open said turbines to the passage of water therethrough, whereby the downward movement of said float causes the water to flow through and actuate the lower turbine and the upwardly movement of said float causes the water to flow through and actuate the upper turbine. 100

Signed at Chicago, county of Cook and State of Illinois, this 30th day of May, 1921.

LEON MITELMAN.
